BRICK-KILN.

1,168,575.

Specification of Letters Patent.

Patented Jan. 18, 1916.

Application filed February 6, 1913. Serial No. 746,477.

To all whom it may concern:

Be it known that we, CHRISTOPHER STEADMAN, a citizen of the United States, residing in Huguenot Park, county of Richmond, 5 State of New York, and HENRY O. ROBINSON, a citizen of the United States, residing in Brookline, Norfolk county, State of Massachusetts, have invented an Improvement in Brick-Kilns, of which the following 10 description, in connection with the accompanying drawings, is a specification, like letters on the drawings representing like parts.

One of the difficulties encountered in utilizing fine grades of anthracite for brick-kiln furnaces has been the impossibility of securing an even burning of the bed of fuel and a proper control and regulation of the fires. While the latter has been attempted by introducing forced-draft devices of various sorts, the realization of a practical system of fire-control, so necessary in brick-burning operations, has failed for one reason or another; with the result that comparatively little brick-burning of this kind has 25 been done on a commercial scale. Our investigations in this field have shown that one of the principal reasons why a proper burning of the fuel, as well as regulation 30 and control of the fires, could not be obtained with the forced-draft, was because the forced-draft device was related to the fuel bed in such a way that the blast tended to blow right through the fuel bed, or to 35 separate the fuel like a wedge, and thus find its way out into the fire chamber. This 40 would have the effect of burning the fuel out entirely in spots, and leaving the rest of the fire only remotely and indirectly affected by the forced-draft, whereby the regulation of the blast itself would not have anything like a corresponding effect upon the fire.

To obviate this difficulty, we have found 45 that if the forced-draft device be so related to the fuel-bed as to deliver downwardly toward the fuel support, the blast will be projected into the fuel-body in such a way as to be first thoroughly divided or committed 50 within the fuel-mass and then to rise gradually and uniformly up through the same in an even-flowing homogeneous column as distinguished from a plurality of spouting jets. Thus will the burning be uniform, and any regulation of the forced-draft

will be able to produce a corresponding and uniform effect upon the fires.

In the drawings, a sufficient portion of a 60 brick-kiln is shown to illustrate the improvement.

Figure 1 being a view in section through the lower part or floor of the kiln, the section-plane being parallel with the front wall. Fig. 2 showing the same parts in a section the plane of which is perpendicular to that of Fig. 1, and, Fig. 3 being 65 a plan view of the floor of the kiln, shown on a much smaller scale.

The floor of the kiln, denoted by *a*, is 70 preferably of masonry so as to be permanent, and fuel spaces *b*, which with the corresponding spaces above formed by the arches of green brick (dotted lines) constitute the fire-chambers of the kiln, are built or formed in this permanent floor. These 75 spaces *b* are not a necessity, because the fuel may rest wholly within the arches of green brick upon a support level with the surface of the kiln-floor. However, where this is 80 so, it has been found desirable to seal upon the side walls of green brick to a point above the fuel-level so that the forced-draft cannot leak through said walls from within the fuel bed, a circumstance which tends both 85 to decrease the efficiency of the draft-control and that of the gases of combustion which reach the upper parts of the kiln. Hence, to obviate the sealing of the walls of green brick around the fuel bed, it is preferable 90 to provide the fuel-spaces *b*.

Each fire-chamber is built within the outer wall *c* of the kiln, opens to the outside through a door *f* and to the interior of the kiln through the arches and spaces 95 formed by the green brick.

In each of the fire-chambers is a long pipe or hollow burner *d* having its underside perforated along the bottom throughout its entire length to form discharge openings *d*³ 100 for delivering air or other combustion-supporting element to the fuel-body which is denoted by *i* and is shown covering the pipe. The latter rests upon the bottom of the fire-chamber and is provided with a short section *d*² located outside the furnace 105 at an angle to the main portion, and an upright portion *e*, also outside the furnace and into the open end of which the air to form the draft is entrained or other- 110

wise delivered. This pipe can be readily set up in position when the kiln is being built and removed when the kiln is burned. For the purpose of supplying the draft, an air or steam duct *h* is set along the outside of the wall *c* and a feeder terminating in a valve *g* leads therefrom to each hollow burner *d*, as shown. It will be understood, of course, that the main *h* is connected to an air compressor or steam supply to furnish the required pressure.

When the kiln is being burned, it will be seen that the air or other gas issuing from the openings *d* underneath the burner will be delivered against the bottom of the kiln or upon any fuel thereunder, and the force of the blast will be destroyed and the air or gas comminuted so that it will rise uniformly through the fuel bed, thus effectively promoting combustion throughout the fuel-body.

It will of course be obvious that the invention is applicable to different kinds of fuel, notwithstanding that it has been developed by us with particular reference to fine grades of anthracite. Moreover, it

should be understood that while it is has been described and explained in connection with the burning of ordinary brick, it is not limited thereto: and that the term "kiln" or "brick kiln" as used throughout the specification and in the claim is not used in a limiting sense but rather to indicate a typical case for the application of the invention.

We claim as our invention:

A brick kiln comprising a series of fire-chambers built within its wall, opening to the outside and having also each an opening to the interior of the kiln, a hollow burner in each of said chambers, having discharge passages underneath, an air duct set along the outside of said wall, and a feeder therefrom to each burner.

In testimony whereof, we have signed our names to this specification, in the presence of two subscribing witnesses, this 4th day of February, 1913.

CHRISTOPHER STEADMAN.
HENRY O. ROBINSON.
